UNITED STATES PATENT OFFICE.

JAMES C. FRENCH, OF KENOSHA, WISCONSIN, ASSIGNOR TO FREDERICK C. AUSTIN, OF CHICAGO, ILLINOIS.

CLAM-SHELL-BUCKET APPARATUS.

1,246,578.

Specification of Letters Patent. Patented Nov. 13, 1917.

Application filed April 5, 1915. Serial No. 19,130.

To all whom it may concern:

Be it known that I, JAMES C. FRENCH, a citizen of the United States of America, and resident of Kenosha, Kenosha county, 5 Wisconsin, (510 Exchange street,) have invented a certain new and useful Improvement in Clam-Shell-Bucket Apparatus, of which the following is a specification.

This invention relates to traveling bucket 10 apparatus for use in conjunction with street paving machines of the kind in which the materials are mixed in a suitable receptacle and then discharged into a bucket by which the mixture is conveyed to the point of discharge on the street.

Generally stated, the object of the invention is to provide a novel and efficient form of bucket for conveying the mixture from the machine to the point of discharge, and 20 means for automatically opening and closing the bucket at the bottom thereof, thereby facilitating the operation of the apparatus, as will hereinafter more fully appear.

It is also an object to provide certain 25 details and features of construction and combinations tending to increase the general efficiency and serviceability of a traveling bucket apparatus of this particular character.

30 To these and other useful ends the invention consists in matters hereinafter set forth and claimed.

In the accompanying drawings—

Figure 1 is a side elevation of a traveling 35 bucket apparatus embodying the principles of said invention, showing the adjacent portions of the mixing machine, which latter may be of any suitable or known character.

Fig. 2 is an enlarged vertical section on 40 line 2—2 in Fig. 1.

Fig. 3 is an enlarged detail section on line 3—3 in Fig. 4.

Fig. 4 is an enlarged plan of the mechanism which supports the bucket on the track 45 or runway, showing the adjacent portions of the latter.

Fig. 5 is a similar section on line 4—4 in Fig. 4.

As thus illustrated, this invention 50 comprises a body frame A upon which is suitably supported the rotary mixing receptacle B, the latter being of any suitable character. Upon this frame is also mounted the hollow swivel C, which latter has a vertical 55 axis, the overhead sheaves D and E, and

the winding drums F and G, the latter being suitably connected by a gear *f* with the large gear-ring *b* on the rotary receptacle. The hollow or tubular swivel C is provided with a segmental worm wheel *c* which is engaged 60 by the worm *H* suitably mounted on the frame and driven by a sprocket connection *h*, the latter being operated in any suitable manner, whereby the said swivel may be oscillated about its vertical axis. Clutches 65 of any suitable character, controlled by a hand lever I, as will be readily understood, may be employed for controlling the rotation of the drums F and G, it being understood, as will hereinafter more fully appear, 70 that these drums constitute the means for operating the bucket apparatus. Any suitable means can be employed for furnishing the power to operate said mixing receptacle, to drive the said drums, and for operating 75 the sprocket connection *h* which transmits the power for oscillating said swivel.

The bucket apparatus comprises a bucket J which may be of any suitable construction, but which, as shown, has the general 80 form of a socalled clam shell bucket, being composed of two halves which are hinged together at *j*, whereby separation of these halves, about their pivotal connection, as shown in dotted lines in Fig. 1, serves in 85 effect to open the bottom of the bucket and thereby discharge the load. The two halves of said bucket are supported by upwardly converging pivoted arms K which are pivoted to the two halves of the bucket at *k*, 90 the upper ends of said arms being pivoted on the cheek plates L which are secured to the hollow swivel *l*, the latter being mounted to turn in the lower end of the traveling support or carriage M, whereby the bucket 95 is movable back and forth and also about a vertical axis. The track or runway N is pivoted at *n* to the lower end of the swivel C, whereby said track or runway may be raised or lowered by adjusting the turn-buckle support O in the connection *o* which extends from the outer end of the runway to a suitable point of attachment on the upper end of the body frame. The two sides 100 of the track or runway are spaced apart in any suitable manner and provide rails for the wheels *m* of the said carriage. A journal P is mounted on this carriage, and the drum *p* is loose on said journal, being rigid 105 with the ratchet wheels Q and R, and the 110

sprocket wheel or pinion S is also loosely mounted on said journal, being provided with ratchet dogs s for engaging the ratchet Q to wind the rope T upon the said drum when the said pinion or toothed wheel S is rotated in the direction of the arrow. This rope T is connected by rods t with the pivot joint j of the bucket. A locking dog U is pivoted on the carriage, in any suitable manner, and arranged to engage the ratchet wheel R, thereby holding the rope or cable T in wound up condition on the drum, thus holding the two halves of the bucket against separation while carrying the load. Rack teeth V, of any suitable form, such as rollers disposed between and suitably mounted on the rails N, are disposed near the mixing machine and in position to engage the sprocket or pinion S when the bucket approaches said machine, thereby winding up the rope T and closing the bucket automatically before it reaches the position for receiving the load.

A cable W is attached to the outer side of the carriage M and arranged to travel around a sheave w at the outer end of the runway, thence under one of the two sheaves X, the latter being arranged side by side below the swivel C, thence upward through said swivel and over one of the sheaves E, the latter being arranged side by side, then over one of the sheaves D which are also arranged side by side, and then down to the drum F by which this cable is operated to draw the bucket toward the outer end of the runway. Another cable Y is suitably attached to the carriage M, and also to the locking-dog U at u, said cable then extending under the other sheave X, thence upward through the swivel C, then over the other sheave E, and then down to the drum G by which the bucket is drawn toward the mixing machine.

With the wheels c and b the bucket can swing sidewise and may turn around and dump anywhere along the track. Also, with the swivel l, the bucket can be adjusted on its pivot to receive the load, regardless of the position or direction of the swinging track.

The operation is as follows: When the cable W is operated the bucket is moved to the outer end of the runway, and while passing the rack teeth V the ratchet dogs s slide freely backward over the teeth of the ratchet wheel Q, in a manner that will be readily understood. When the dumping position is reached, as indicated in dotted lines in Fig. 1, the drums are then reversed and a sudden pull on the cable Y jerks the locking dog U out of engagement with the ratchet R, thereby allowing the drum p to rotate and unwind the rope or cable T, thus permitting the weight of the load to separate the two halves of the bucket, causing the desired dis-

charge of the mixture on the street. The continued movement of the bucket toward the mixing machine finally brings the pinion S into engagement with the rack V, thereby winding up the cable T and restoring the bucket to its normal condition for receiving the next load. Thus the bucket is again locked in carrying position, and a reversal of the drums, after the bucket is loaded, will then cause the cable W to draw the bucket toward the outer end of runway.

The invention, of course, is not limited to the exact construction shown and described.

What I claim as my invention is:—

1. A traveling bucket apparatus comprising a runway, a bucket supported to travel along said runway, bucket-dumping mechanism including a ratchet also traveling with said bucket along said runway, a line to control said mechanism and thereby dump the load, and means on said runway to operate said mechanism and thereby restore said bucket to carrying condition while approaching the loading position thereof.

2. A traveling bucket apparatus comprising a runway, a bucket supported to travel along said runway, bucket-dumping mechanism also traveling with said bucket along said runway, a line to control said mechanism and thereby dump the load, and means on said runway to operate said mechanism and thereby restore said bucket to carrying condition while approaching the loading position thereof, said mechanism including a drum provided with a cable for dumping and restoring said bucket, a pinion for operating said drum, and a rack on said runway to operate said pinion.

3. A traveling bucket apparatus comprising a runway, a bucket supported to travel along said runway, bucket-dumping mechanism also traveling with said bucket along said runway, and means on said runway to operate said mechanism, said mechanism including a winding drum provided with a cable for dumping and restoring said bucket, ratchet wheels rigid with said drum, a pinion having a ratchet dog for engaging one of said ratchet wheels to rotate said drum and thereby move said bucket into carrying position, a locking dog for the other ratchet wheel, a rack on said runway to engage said pinion, means for moving the bucket toward the dumping position, means for moving the bucket toward receiving position, said locking dog being connected with said last mentioned means to automatically release said drum and thereby dump the load when the direction of travel of the bucket is reversed.

4. A traveling bucket apparatus comprising a runway, a bucket having devices by which it is supported to travel along said runway, bucket-dumping mechanism also traveling with said bucket along said runway, a line to control said mechanism and

thereby dump the load, and means on said runway to operate said mechanism and thereby restore said bucket to carrying condition while approaching the loading position thereof, said bucket comprising two clam shell halves constructed with a pivotal connection between them, and said mechanism comprising a winding drum provided with a flexible connection extending downward to operate said halves relative to each other, said devices supporting the bucket at fixed height during the operation of said flexible connection.

5. A traveling bucket apparatus comprising a runway, a bucket supported to travel along said runway, bucket-dumping mechanism also traveling with said bucket along said runway, a line to control said mechanism and thereby dump the load, and means 15 on said runway to operate said mechanism and thereby restore said bucket to carrying condition while approaching the loading position thereof, said mechanism comprising a winding drum operated with a flexible connection extending downward to the bucket, and means including a swivel by which the bucket is supported on the runway, independently of said flexible connection, said swivel having an axial opening for said flexible connection.

6. In combination, a track having a bucket mounted to travel thereon, mechanism to dump the load at any desired point along said track, a swivel to permit rotation of the bucket about a vertical axis, so that the bucket may turn around and dump at any point along said track, devices to operate the bucket along its path of travel, a connection to control said mechanism at will and to 35 return the bucket along said track to loading position, and means to automatically restore the bucket to carrying condition after the dumping of the load, said bucket comprising pivotally-connected sections adapted to 40 swing apart to dump the load, and said mechanism having means extending through said swivel to control the pivotal movements of the two sections.

7. In combination, a track having a bucket 50 mounted to travel thereon, a swivel to permit rotation of the bucket about a vertical axis, so that the bucket may turn around and dump at any point along said track, mech-

anism to dump the load at any desired point along said track, and to automatically restore the bucket to carrying condition while in any rotated position on said swivel, after dumping the load, devices to operate the bucket along its path of travel, and a connection to control said mechanism at will 55 and to return the bucket along said track to loading position, said bucket comprising pivotally connected sections adapted to swing apart to dump the load, and said mechanism having means extending through said swivel 60 to control the pivotal movements of the two sections.

8. The structure of claim 6, as stated, said means including a rack on said track and a pinion associated with said mechanism to 70 engage said rack.

9. The structure of claim 7, as stated, said mechanism including a drum and ratchet therefor to release the load and to raise the sections into carrying position.

10. In combination, a track having a bucket mounted to travel thereon, a swivel to permit rotation of the bucket about a vertical axis, so that the bucket may turn around freely at any point along said track, 75 devices to operate the bucket along its path of travel, means for at will controlling the bucket through said swivel to dump the load at any desired point along said track and for returning the bucket to loading position, 80 and means on the track to automatically restore said bucket to carrying condition before it reaches the loading position.

11. The combination of a track, a traveler on said track, a carrying and dumping bucket, a swivel to support said bucket on said traveler, so that said bucket may turn freely about a vertical axis, means to pull the bucket along the track, instrumentalities including a line for at will controlling said bucket to dump the load at any point along said track, and means to automatically restore said bucket to carrying condition after dumping the load and before reaching the loading position.

Signed by me at Chicago, Illinois, this 25th day of March, 1915.

JAMES C. FRENCH.
